PRESSING MACHINE

Martin J. Boriski, Houston, Tex.

Application June 13, 1935, Serial No. 26,525

10 Claims. (Cl. 223—37)

This invention relates to a pressing machine.

An object of the invention is to provide a machine of the character described which is useful in the manufacture of garments, and particularly useful in the formation of the garment pockets.

5 A particular object of the invention is to provide a pressing machine designed for the purpose of pressing back the flaps of material on each side of the pocket slit preparatory to sewing the flaps permanently to the material of the garment in the manufacture of clothing.

10 A further object of the invention is to provide a pressing machine of the character described that may be quickly and easily manipulated, that is, of simple construction, accurate in operation, and which is very durable in use.

15 With the above and other objects in view, the invention has particular relation to certain novel features of construction, operation, and arrangement of parts, an example of which is given in this specification, and illustrated in the accompanying drawings, wherein:—

Fig. 1 shows an end view of the machine.

20 Fig. 2 shows a plan view of the work-receiving platform.

Fig. 3 shows a plan view of the slitted fabric to be operated on by the machine.

25 Fig. 4 shows a plan view of the fabric illustrating the pocket flaps folded back in position for sewing.

Fig. 5 shows a fragmentary cross-sectional view showing the pressure plates in position to receive the fabric to be operated on.

30 Fig. 6 shows a cross-sectional view illustrating the pressure plates in active position.

Fig. 7 shows a perspective view of one of the pressure plates.

35 Fig. 8 shows a longitudinal sectional view illustrating the pressure plates in inactive, or work-receiving position, and

Fig. 9 shows a similar view showing the plates in active position.

40 Referring now more particularly to the drawings, wherein like numerals of reference designate the same parts in each of the figures, the numeral 1 designates a table which is supported on suitable corner legs 2. Secured on this table is a supporting framework preferably composed of the U-frames 3, 3, the cross-bar connecting the upstanding arms of the frames being bolted on to the top of the table, as illustrated in Fig. 1, said U-frames being suitably spaced apart, as illustrated in Figs. 8 and 9.

45 On this framework is the work-receiving platform 4 having the central longitudinal slot 5

therethrough. Each U-frame 3 is provided with a central upstanding rod 6, the lower ends of the rods being supported on the cross-bars of the U-frames 3 and their upper ends being anchored to the platform 4 above.

5 There is a longitudinal yoke 7 whose ends are provided with the vertically aligned end bearings 8, 8, which slide on the corresponding rods 6.

There is a treadle 9 pivoted, at one end, to a cross-bar 10 which is secured to the legs 2 at one side of the table. A connecting link 11 is pivoted, at its lower end, to the treadle 9, and this link is fastened at its upper end to the yoke 7. The link may be formed of sections bolted together, as shown in Fig. 1, thus providing for adjustments 10 of the link in length.

15 Secured on opposite sides of the yoke 7 are the bearings 12, 13, the corresponding bearings at each end of the yoke forming a pair. In the bearings 12, there is a rod 14, one end of which is turned outwardly at right angles to the rod, and extended across the yoke forming the arm 15. In the bearings 13, there is a rod 16, one end of which is outwardly turned at right angles to said rod 16 and extended across the yoke forming an 20 arm 17, the arms 15 and 17 being arranged at opposite ends of the respective rods 14 and 16, as more clearly illustrated in Figs. 1, 8, and 9.

25 Flexible connecting members 18, 18, are connected at their upper ends to the free ends of 30 the arms 15, 17, and at their lower ends to the treadle 9. The rod 14 has the upstanding fingers 19, 19, secured thereto and the rod 16 has similar upstanding fingers 20, 20, secured thereto.

35 A pair of levers 21, 21, are pivotally connected at their lower ends to the upper margin of the yoke 7 on one side, and a pair of similar levers 22, 22, are pivoted at their lower ends to the upper margin of the yoke 7 on the other side, said levers 21 and 22 being in alignment with the corresponding fingers 19, 20. There are the oppositely arranged pressure plates 23, 24, which are similar in shape and construction, and one of which is illustrated in detail in Fig. 7. These pressure plates are arranged to work through the slot 5 40 of the work platform 4 in a manner and for a purpose hereinafter to be described.

45 The ends of the pressure plates have the extended pintles 25 which ride along the arcuate tracks 26 that are formed in the depending 50 flanges 27 carried by the underside of the work platform 4 and secured thereto. The upper, or free, margin of each pressure plate is overturned at approximately a right angle to the main body of the plate forming the lips 28, 28, 55

which work through the slot 5, and the upper ends of the levers 21, 22, are pivotally connected to the other margins of the respective plates.

5 Pull-springs 29, 29, are attached, at their outer ends, to the downwardly turned margins 4', 4', of the work platform 4, and the inner ends of these springs are connected to the brackets 30, 30, which are attached to the outer sides of the respective levers 21, 22. A coil spring 31 is connected at its lower end to the treadle 9, and at its upper end to the table 1, and the coil springs 32, 32, are connected at their lower ends to opposite sides of the link 11, and at their upper ends to said table.

10 15 These springs 31, 32, normally hold treadle 9, as well as the link 11 and yoke 7 in elevated position, and when in this position the links 21, 22, will be held in their outward position, as shown in Fig. 5, by the springs 29, 29, with the pressure plates 23, 24, lying closely against the underside of the work platform, and the lips 28, 28, projected vertically through the slot 5. The underside of the platform 4 is provided with indentations 33 which provides spaces for hinges connecting the levers 21, 22, to the pressure plates, as illustrated in Fig. 5, so that the main body of each plate may lie closely against the underside of the work platform.

20 25 When in this position, the slitted fabric shown in Fig. 3 may be placed on the work platform with the lips 28 projected upwardly through the slit 34. The treadle 9 may then be depressed, pulling the arms 15, 17, downwardly and operating through the link 11 to pull the yoke 7 downwardly also. As the arms 15, 17, are moved downwardly, the corresponding rods 14, 16, will be partly rotated, carrying the free ends of fingers 19, 20, into engagement with the outer sides of the corresponding levers 21, 22, and 30 forcing said levers inwardly into approximately parallel relation, as shown in Fig. 6. This will cause the outer margins of the pressure plates 23, 24, to swing downwardly and inwardly carrying said pressure plates into approximately parallel relation, as shown in Fig. 6, and swinging the lips 28, 28, outwardly, overturning the flaps 35, 35, of the fabric, and pressing said flaps downwardly into folded position against the surrounding fabric of the pocket being formed. Underneath the work platform around the slot 5, there is an electrical heater 36 which is connected with a source of electrical supply through the wiring 37 whereby the work platform is heated opposite the folded fabric. The pressure is applied for a sufficient length of time to properly crease the fabric to maintain the flaps in place until they are permanently sewed. Upon release of the treadle 9, the springs 29, 31, 32, will return the parts to their original, or inactive 45 position, and the formed garment pattern may be removed and another substituted for it, and the operation repeated.

50 The drawings and description disclose what is now considered to be a preferred form of the invention by way of illustration only while the broad principle of the invention will be defined by the appended claims.

55 What I claim is:

1. A pressing machine comprising a work supporting platform having a slot, pressure plates arranged underneath the platform and having lips arranged to work through the slot and normally in approximately parallel relation to project through a slit in fabric positioned on the platform, means for actuating the plates to move the

55 lips into approximately parallel relation with the platform to clamp the fabric forming the margins of the slit against the platform.

2. A pressing machine comprising a work support for fabric, said support having a slot, lips 5 working through the slot and normally in parallel relation to project through a slit in the fabric, means for moving the lips in opposite directions into parallel relation with the support to fold back the margins of the slit and to clamp the 10 folded back material between the lips and support.

15 3. A pressing machine comprising a work support for fabric, said support having a slot, pressure plates movably mounted underneath the support and having margins which work through the slot and are movable into work-receiving position in approximately parallel relation to project through a slit in the fabric placed on the support, said plates being also movable into position to carry said margins into clamping relation with 20 the support whereby the fabric about the slit may be clamped between said margins and the support.

25 4. A pressing machine comprising a work platform having a slot and adapted to receive and support a slitted fabric with the slit thereof aligned with said slot, clamps arranged to work through the slot and to be received by said slit and means arranged to actuate the clamps into position to retract the margins of the slit into 30 folded position and to clamp the folded portions firmly against the platform.

35 5. A pressing machine comprising a work platform having a slot and adapted to receive and support a slitted fabric with the slit thereof aligned with said slot, clamps arranged to work through the slot and to be received by said slit and means arranged to actuate the clamps into position to retract the margins of the slit into 40 folded position and to clamp the folded portions firmly against the platform, and means for heating the platform adjacent the slot.

45 6. A pressing machine comprising a platform having a slot, clamp members underneath the platform and movable into active and inactive positions, said clamp members having overturned margins which project through the slot in approximately parallel relation when the clamp members are in inactive position, said overturned margins, when in inactive position being arranged to project through the slit of a slitted fabric on the platform, manually operable means arranged to actuate the clamp members into active position whereby said overturned margins are moved into clamping relation with the platform to clamp the fabric about the margins of 50 said slot.

55 7. A pressing machine comprising a work-receiving platform having a slot, a vertically movable yoke beneath the platform, clamp members 60 beneath the platform having overturned lips arranged to work through said slot and through a slit in fabric material on the platform, means normally holding the clamp members in position to project said lips through said slot, levers connecting the yoke with the clamp members, means through which the yoke may be moved downwardly to effect the actuation of the clamp members whereby said lips are moved through said slot into clamping relation with the table to clamp 65 the fabric between them and said table.

70 8. A pressing machine comprising a work-receiving platform having a slot, a vertically movable yoke beneath the platform, clamp members beneath the platform having overturned lips ar- 75

ranged to work through said slot and through a slit in fabric material on the platform, means normally holding the clamp members in position to project said lips through said slot, levers connecting the yoke with the clamp members, means through which the yoke may be moved downwardly to effect the actuation of the clamp members whereby said lips are moved through said slot into clamping relation with the table to clamp the fabric between them and said table, 10 said clamp-actuating means including, also, means to move said levers inwardly into approximately parallel relation upon the downward movement of said yoke.

15 9. A pressing machine comprising a work-receiving platform having a slot, a vertically movable yoke beneath the platform, clamp members beneath the platform having overturned lips arranged to work through said slot and through 20 a slit in fabric material on the platform, means normally holding the clamp members in position to project said lips through said slot, levers

connecting the yoke with the clamp members, means through which the yoke may be moved downwardly to effect the actuation of the clamp members whereby said lips are moved through said slot into clamping relation with the table, 5 to clamp the fabric between them and said table, and yieldable means normally tending to move the yoke upwardly.

10. A pressing machine comprising a work platform having a slot therethrough, clamp 10 members underneath the table formed with overturned lips arranged to work through said slot, yieldable means normally holding said clamp members in said position, a vertically movable yoke beneath the platform, levers connecting said 15 yoke and clamp members, means for moving the yoke downwardly and the levers inwardly to effect the actuation of the clamp members to move said lips into clamping relation with the platform and means normally tending to elevate the yoke. 20
